UNITED STATES PATENT OFFICE

101,423

DESIGN FOR A COAT

Milton E. Davis, New York, N. Y.

Application August 11, 1936, Serial No. 64,360

Term of patent 3½ years

To all whom it may concern:

Be it known that I, Milton E. Davis, a citizen of the United States of America, residing in Manhattan, county of New York and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The characteristic feature of my design resides in the broad shoulders of the sport coat, as shown, which shoulders are characterized by truncated triangular inserts extending from the shoulder to the collar, said inserts having cleft-like gathers projecting from the base of same, as shown, giving an epaulet appearance to the garment.

I claim:

The ornamental design for a coat, substantially as shown and described.

MILTON E. DAVIS.
